UNITED STATES PATENT OFFICE.

WILLIAM E. WHITE, OF CHICAGO, ILLINOIS, ASSIGNOR TO KALMAN STEEL COMPANY, OF CHICAGO, ILLINOIS, A CORPORATION OF DELAWARE.

BAR SUPPORT AND SPACER.

Application filed May 28, 1927. Serial No. 195,003.

My invention relates to improvements in road construction, and more particularly to a support and spacer for the reinforcing bars in roads.

It is well known that bar supports and bar chairs have been in common use in the construction of roads for some time, as well as ingenious devices of various kinds for spacing the reinforcing bars from the side frame of the roadway. But the device of my invention combines a bar chair and a spacer in a simply operated, cheap and highly efficient device which is intended to overcome all the objections to bar chairs and spacers heretofore devised.

One of the objects of my invention is to provide a bar support and spacer that is light in weight, easily operated at low cost by inexperienced labor, and highly efficient.

Another object of the device of my invention is that of providing a spacing and supporting means, together with means for securely locking the reinforcing bar in place.

The invention herein contemplated will be more readily understood by reference to the accompanying drawing, in which;

Fig. 1 is an elevation of a bar support and spacer constructed according to my invention;

Fig. 2 is a front elevation thereof;

Fig. 3 is a plan view thereof;

Fig. 4 is a view of the blank from which the support is formed.

In Fig. 1 of the drawings, I have illustrated the device of my invention in operative position in full lines and in initial position in dotted lines. The device comprises essentially a support composed of sheet metal, and a combined pin and spacer composed of a wire rod. The support is formed from a flat section of metal, 10, as shown in Fig. 4, preferably constructed with a notch 11 in one end for a purpose later described. By means of suitable dies, the flat section of metal is bent into the form best shown in Fig. 1, having a straight portion 12 of hollow cylindrical form and angularly bent channel shaped ends, 13, 14, constituting a head and foot respectively. Due to the channel shape at the intersection of the head and foot with

the straight portion, the strength of the said portions against a downwardly applied force is increased.

The wire rod member comprises a straight pin, 15, closely fitting the cylindrical portion 12 and frictionally held therein. At the junction of the pin and the spacing arm 16 I provide a loop 17 located immediately above the head, 13. The connecting portion 18 between the loop and the arm 16 lies in the plane of the notch 11 and when the parts are in operative position, the portion 18 occupies the notch 11 and prevents oscillation of the arm around the axis of the pin.

The parts are constructed, shipped and handled in the dotted line position of Fig. 1. When the device is to be used, it is placed in position to receive a bar 19 which rests on the head, 13, the extremity of the arm 16 contacting the side form of the pavement. Thereafter, either by hand pressure or by blows applied to the top of the loop, the pin is forced into the soil until the parts assume the full line position of Fig. 1. When in this position the bar is firmly held against movement laterally and vertically. The arm rests in contact with the side form and serves as a secure means for holding the pin against movement while the concrete is being poured and tamped.

The device is of extreme simplicity, may be cheaply manufactured and constitutes an advance in the art. Modifications may be made without departure from the spirit of my invention, and I do not wish to be limited except as indicated in the appended claims.

I claim:

1. In combination, a support having a straight portion, a foot and a head, the straight portion being in the form of a hollow cylinder, a pin slidably fitting within said cylinder, an arm formed integral with said pin, a loop being provided at the junction of the pin and arm, a bar being adapted to be supported on the head and held within said loop and means on the head adapted to cooperate with the arm when in final position to prevent oscillation of the arm.

2. In combination, a sheet metal support having a cylindrical body and generally chan-

nel shaped head and foot integral therewith, a wire rod bent to provide a vertical pin and a lateral arm with a loop at the junction thereof, the pin being fitted to frictionally slide within the cylinder, the loop being adapted to receive a bar, the bar resting on the said head, and means on the head for engaging the rod when in operative position to prevent oscillation of the arm.

10 In testimony whereof I have affixed my signature.

WILLIAM E. WHITE.
